COMMERCIAL SWINGABLE BURNER UNIT

Walter Kennedy, Cliffside Park, N. J.; The United National Bank of Cliffside Park, Bergen County, N. J., administrator of said Walter Kennedy, deceased, assignor to William D. Kennedy, Englewood, N. J.

Application February 11, 1949, Serial No. 75,759

2 Claims. (Cl. 126—39)

1

This invention relates to burners of the type and kind generally employed in restaurants, lunchrooms and similar places. More particularly, the invention deals with a burner unit which is mounted to swing from a normal operative position, to a raised or perpendicular position to facilitate cleaning and repair to the burner, as well as the counter or table surface disposed beneath the burner. Still more particularly, the invention deals with a burner unit of the character described having means adapting the same for use with stove accessories, such for example, as broilers.

The novel features of the invention will be best understood from the following descriptions when taken together with the accompanying drawing in which certain embodiments of the invention are disclosed, and in which the separate parts are designated by suitable reference characters in each of the views, and in which:

Fig. 1 is a plan and sectional view of a burner unit made according to my invention, with part of the construction broken away.

Fig. 2 is a section on the line 2—2 of Fig. 1, on an enlarged scale, with part of the construction broken away and indicating in dotted lines, the raised position of the unit.

Fig. 3 is a partial section on the line 3—3 of Fig. 1, on an enlarged scale, and indicating part of a broiler.

Fig. 4 is a partial section on the line 4—4 of Fig. 2; and

Fig. 5 is a partial section on the line 5—5 of Fig. 4.

In the drawing, 10 represents what I term a swingable burner unit which, as indicated in Fig. 2, is adapted for mounting on a counter or other support 11 to normally assume a horizontal position thereon, as shown in full lines and to be raised to a vertical position at the back of the counter, as indicated in part, in dotted lines in said figure. In the construction shown, the unit 10 is economically constructed from a U-shaped strip or band, fashioned to form a front wall portion 12 and side walls 13 and 14, this U-shaped structure forming the frame of the unit, which is pivoted to a fixed angle-iron strip 15, secured to the rear portion of the counter 11, the pivot being formed by pins 16 and 17 arranged in up-standing end bearing walls 18 and 19 on the strip 15.

Considering Fig. 3 of the drawing, it will appear that these bearing walls extend well above the vertical back portion 20 of the angle-iron strip. Arranged upon the frame is a top grill

2

plate 21, which forms a cover for the top of the frame or the burner unit and this grill plate can be detachably mounted in any desired manner. The plate has an aperture 22 therein, note Fig. 3, to facilitate coupling of a broiler, as later described.

Joining the walls 13 and 14, inwardly of the pivots 16 and 17, is a cross-strap or bar 23, which forms a support for one of a number of gas burners 24, only one of which is shown in the accompanying drawing, as well as a support for a gas service or supply pipe 25 for servicing the broiler, as later described. The burners 24 may be of any desired construction, as will be apparent.

Mounted in the frame of the unit 10, on the inner surface of the front wall 12 of the frame, is a long gas supply tube 26, preferably having a free mounting in the side walls 13 and 14, as indicated by the clearance in the aperture 27, inwardly of the supporting pin 28. This mounting facilitates alinement of the tube 26 with the swinging mounting of the gas supply pipe 29, which couples with the tube 26. The pipe 29 has at its inner end, a coupling 30, having a conical ground seat in opposed walls thereof, as seen at 31, for a conical extension 32 on a fitting 33. The conical extension 32 is apertured, as seen at 34, for supply of gas to the pipe 29, and thus to the supply tube 26. On the extension 32 is an outwardly projecting threaded rod or reduced threaded portion 35 for reception of a nut 36 to control tensioning of a spring 37, which means the tapered extension 32 is in seated position in the bores 31, as will be apparent. The taper is exaggerated in the accompanying drawing simply from a standpoint of clarification, and it will also be apparent that the extent of the bearing surfaces 31 can be varied.

The fitting 33 comprises a relatively high tubular body 38, from which the extension 32 extends at the upper portion thereof, as clearly seen in Fig. 5, the gas supply pipe or a fitting thereon, as at 39, being coupled with the tubular body 38, as clearly seen in Fig. 4 of the drawing. The fitting 39 passes through the back wall 20 and is threaded into the tubular body 38 and a nut 40 is employed to secure the parts in firm engagement with a fixed angle-iron strip 15. To avoid strains on the fitting 33, as a whole, the tubular body has an extension 41, with a pin 42 arranged in the wall 20, to act as a key.

Considering Figs. 2 and 4 of the drawing, it will be apparent that the axis of the extension 32 is in direct alinement with the pivots 16 and 17,

so that in swinging the unit vertically, the pipe 29 swings on the extension 32, thus maintaining constant supply of fuel at all times to the tube 26 and the burners. It will be understood that this will maintain the conventional pilot lights which are employed in burners of the kind under consideration in operation. Pilot lights are not shown, as they form no part of the present conception.

In Fig. 1 of the drawing, the unit 10 is broken away and only one burner 24 is shown. However, a number of these burners may be employed, and each burner will have a control valve, as at 43, note Fig. 2, directly coupled with the tube 26 and having a fingerpiece portion 44 disposed outwardly of the front wall 12. At the rear end of the valve is the usual Venturi tube 45, leading to the burner 24, to control admission of air supply to the burner.

The rear end of the pipe 25 has a fitting 46 having an upwardly directed gas discharged nozzle 47 which extends above the frame and through the aperture 22 in the plate 21. The aperture 22 facilitates reception of the downwardly extending Venturi tube 48 of a broiler, part of which is indicated in dot and dash lines at 49 in Fig. 3. The broiler can be of the general type and kind disclosed in my prior application Ser. No. 58,569 filed November 5, 1948, in which a similar type of tube is employed. The tube 48 includes an adjustable apertured sleeve 50 which acts as an air valve controlling the supply of air to the Venturi tube 48.

From the foregoing, it will be apparent that such accessories as a broiler can be arranged upon the plate 21 and be serviced from the supply pipe 25, which has a valve control forwardly of the front wall 12, as seen at 43'. In other words, similar to the fingerpiece control 44 of the valve 43.

With a burner unit of the character described, it will be apparent that the entire unit can be swung from the full line horizontal position, seen in Fig. 2, to a raised position at the back of a counter or table 11, facilitating cleaning of the various parts of the unit, as well as the upper surface of the counter or table. When the unit is in the raised position, the counter or table can be utilized for other purposes. In raising the unit, the plate 21 can be removed so as to clean the upper structure of the unit prior to moving the same into the raised position and all of the foreign matter or removed particles will collect on the counter and can then be removed therefrom, or a collecting sheet can be first disposed on the counter before the cleaning operations are performed.

It will be understood that my invention is adapted for use in connection with units of any type or kind and using any type or kind of burners. In this connection, the grill plate can be of such structure as to fully expose some of the burners for direct heating of receptacles arranged thereover.

By constructing the unit of the metal strips and other parts, it will be readily seen that the unit 65 can be constructed very economically. The only parts which are of special construction are the fittings 30, 33 and 46. All other fittings, pipes and the like can be of standard construction.

Throughout the specification, reference is made 70 to a counter or table top, and it is understood that

this counter or table top may comprise any relatively flat horizontal supporting surface upon which the burner unit is arranged. In some instances it may comprise the top of a range. The 5 distinctive feature in the present invention resides in the provision of the swinging frame supporting burner or similar service mediums, so that at any time, the unit can be swung into a raised position for cleaning or other purposes, as herein set forth.

Having fully described my invention, what I claim as new and desire to secure by Letters Patent is:

1. The combination with a counter having an 15 elongated frame strip fixed along and projecting above the upper surface of the rear portion thereof, said strip having longitudinal bottom and back portions, and upwardly directed pivot ends, of a swingable burner unit adapted to mount a plurality of gas accessories, a plurality of gas accessories in said unit, said unit comprising a U-frame pivotally supported in connection with the pivot ends of said frame strip, said U-frame comprising front and side members, means paralleling the frame strip for joining and bracing the side members of said swingable U-frame adjacent pivot ends thereof, said means adapted to form a support for said gas accessories, a gas supply tube arranged longitudinally and inward of the front member 20 of the U-frame and adapted to be coupled with said accessories, means mounted on the frame strip forming a gas supply fitting, said fitting having a discharge portion arranged in alignment with the pivot axis of said swinging frame, and a gas supply pipe arranged within said U-frame and swingably mounted on said discharge portion and coupled with said gas supply tube in providing gas supply to the fittings of said unit.

2. A swingable gas burner unit of the class described, 40 said unit comprising an elongated fixed frame having longitudinal bottom and back walls and upwardly extending ends, a fitting fixed in said frame and forming a gas supply to said unit, said unit comprising a U-shaped frame swingably mounted on said fixed frame, said swingable frame comprising front and side members, the ends of the side members being pivoted to the ends of said fixed frame, means joining side members of said swingable frame adjacent the pivot ends thereof, a gas burner supported on said means, means within said swingable frame and having a pivotal mounting on said fitting for providing a constant gas supply to the burner of said unit in the different positions thereof, and a grill plate detachable with said swinging frame and forming a top cover for the swinging frame when in horizontal position.

WALTER KENNEDY.
